UNITED STATES PATENT OFFICE.

EDWARD W. CARPENTER, OF BRIDGEPORT, CONNECTICUT.

LOOSE-LEAF BINDER.

Application filed August 28, 1923. Serial No. 659,737.

To all whom it may concern:

Be it known that I, EDWARD W. CARPENTER, a citizen of the United States, residing at Bridgeport, county of Fairfield, State of Connecticut, have invented a new and useful Loose-Leaf Binder, of which the following is a specification.

This invention relates to loose leaf binders of the type in which there are one or 10 more sets of oppositely disposed complementary arched arms, the free ends of which are separable to allow for insertion or removal of the loose leaves, and may then be pressed together to secure the leaves 15 thereon, and in which resilient means is provided for holding these arms either in open or closed position.

It is an object of the invention to simplify the construction of this type of binder 20 by reducing the number of parts and making the parts less complicated so that the device will require less metal, may be more cheaply manufactured, will be less liable to get out of order and thus will be more 25 reliable and efficient in operation.

With the foregoing and other objects in view, I have devised the construction illustrated in the accompanying drawing, in which

30 Fig. 1 is a top plan view of my improved binder showing the securing arms in open position.

Fig. 2 is a bottom plan view showing the arms in closed position.

35 Fig. 3 is a side elevation at one end thereof.

Figure 4 is a transverse section showing the arms closed.

40 Fig. 5 is a transverse section substantially on line 5—5 of Fig. 1 and corresponding to Fig. 4 with the arms in open position.

Fig. 6 is a transverse section substantially on line 6—6 of Fig. 2, and

45 Fig. 7 is an end elevation looking from the bottom of Fig. 1.

My improved binder comprises a back plate 10 of suitable resilient sheet metal, and the opposite sides 11 thereof are bent laterally longitudinally of the body and in 50 spaced relation so that the plate is substantially U-shaped in cross section, as shown in Figs. 4 to 7. At its opposite ends the body of the plate is provided with suitable lugs or ears 12 having openings 13 whereby 55 the plate may be secured to any suitable support.

Located between the sides 11 of the back plate is a pair of rods 14 which extend longitudinally of the plate and engage the sides 11. At suitable positions, preferably 60 adjacent their opposite ends, these rods are offset towards each other as shown at 15, and these offsets are connected by suitable toggle connections. Preferably this connection is formed by providing a groove or recess 16 in 65 one of the rods and a projecting tongue 17 in the other rod adapted to seat in the groove or recess. This tongue and groove forms a pivotal connection between the two rods, and they are held in engagement by 70 the sides 11 of the back plate. The rods 14 are provided with oppositely disposed complementary curved or arched arms 18 and 19 extending at substantially right angles to 75 the body of the rod. To provide a pivotal connection between the rods and the back plate this plate is provided with a plurality of openings 20 through which these arms extend, and each arm rests on one side of its opening to provide a pivotal connection or support for the rod in the plate and on opposite sides of the toggle connection 16—17. 80

The operation is as follows:

The pivots 21 for the arms 18 and 19 on 85 the sides of the openings 20 are so arranged that when the free ends of the arms are moved toward and from each other the toggle connection 16—17 will pass through a line joining these pivotal connections from one side to the other thereof, and thus with 90 the sides 11, through the resiliency of the plate, form a spring operated toggle. For example, when the free ends of the arms are moved from the closed position shown in Fig. 4 to the open or separated position shown in Fig. 5, the tongue and groove connection 16—17 is passed upwardly from a point below the pivotal bearing of the arms 18 and 19 on the edge of the openings 20, as 95 shown at 21, to a position above these bearings, as shown in Fig. 5. During the first part of this movement the toggle connection separates the sides 11 against the resiliency of the plate, and then as the tongue and groove connection passes above these pivots the resiliency of the plate tends to force these sides together and hold the free ends of the arms 18 and 19 separated, as shown in Fig. 5. The same resiliency of the plate tends to hold the ends of the arms together 100 or closed, as shown in Fig. 4. When the arms are opened the body of the plate forms 105

a limit stop to limit the movement of the offsets 15 and to prevent the arms opening too far. This action is illustrated in Fig. 5. The ends of the arms 18 and 19 are preferably mated, one of them being provided with a groove 22 and the other with a correspondingly shaped end 23 to fit this groove.

In assembling, the sides 11 are bent only part way to the position shown in Fig. 2. 10 The rods 14 are then placed in position with the arms 18 and 19 extending through the openings 20, and with the tongue 17 in the grooves or recesses 16. Pressure is then applied laterally to the sides 11 bringing them 15 tightly against the body portions of the rods, after which operation the resiliency of the plate will hold the rods in position with the tongues 17 and the grooves 16 in engagement.

20 It will be obvious from the foregoing description that the binder is extremely simple in construction requiring the minimum number of parts, which parts are themselves very simple in construction. Thus the device may be manufactured at low cost and is very unlikely to get out of order. The type of toggle connection between the rods illustrated, that is the tongue and groove, is old and well-known in this type of devices, but in prior devices the edges of the sides of the back plate were curved over the rods to secure the rods in the back plate and to provide a pivotal connection between them. By providing the openings 20, however, and have laterally extending portions 30 of the rods rest on edges of these openings, a pivotal connection is provided between the rods and the plate, and the rods will be securely fastened to the plate without the necessity of lapping the plate around the rod, which is an expensive and difficult operation. Besides it requires a greater amount 40 of metal than is required with the construction of the applicant's device.

45 Having thus set forth the nature of my invention, what I claim is:

1. In a loose leaf binder, a back plate provided with openings, a pair of rods provided with oppositely disposed complementary 50 arched arms extending through said openings, the sides of the openings extending beneath the arms to form bearings therefor, a toggle connection between said rods, and resilient means coacting with said toggle to hold the arms either together or separated.

55 2. In a loose leaf binder, a resilient back plate provided with openings, a pair of rods provided with oppositely disposed complementary arched arms extending through said 60 openings, the sides of the openings extending beneath the arms to form bearings there-

for, and a toggle connection between said rods, portions of the plate reacting with said rods to operate the toggles and hold the arms either together or separated.

65 3. In a loose leaf binder, a resilient back plate substantially U-shaped in cross section and provided with a plurality of openings, a pair of rods provided with oppositely disposed complementary arched arms extending through said openings, the sides of the openings extending beneath the arms to form bearings therefor, portions of said rods lying between the sides of the plate and engaged thereby, and a toggle connection between said rods.

70 4. In a loose leaf binder, a resilient back plate with the sides bent laterally from the body and spaced from each other and provided with a plurality of openings, a pair of rods located between said sides and provided with oppositely disposed complementary curved arms extending through said openings, the sides of the openings extending beneath the arms to form bearings therefor, and a toggle connection between said bars, said toggle and the sides of the plate coacting to hold the arms either separated 75 or together.

75 5. In a loose leaf binder, a resilient back plate with the sides bent laterally to the body in spaced relation and provided with a plurality of openings, a pair of rods between said sides in engagement therewith and provided with oppositely disposed complementary curved arms extending through said openings, the sides of the openings extending beneath the arms to form bearings therefor, and said rods being provided with offsets toward each other having complementary tongue and groove connections, the sides of the plate and the tongue and groove connections coacting to provide a spring operated toggle to hold the arms either separated or together.

100 6. In a loose leaf binder, a resilient back plate with its sides bent laterally to the body and in spaced relation, a pair of rods between said sides and provided with oppositely disposed complementary curved arms, said plate being provided with a plurality of openings therethrough and the sides of the openings extending beneath the rods to provide them with bearings on the sides of said openings, and a toggle connection between 105 said rods, the sides of the plate and the toggle coacting to turn the rods on said pivots and hold the arms either separated or together.

110 In testimony whereof I affix my signature.

EDWARD W. CARPENTER.
